UNITED STATES PATENT OFFICE.

WILLIAM K. ANDERSON, OF COLORADO SPRINGS, COLORADO.

RAIL-JOINT.

1,147,912.

Specification of Letters Patent. Patented July 27, 1915.

Application filed April 28, 1915. Serial No. 24,553.

To all whom it may concern:

Be it known that I, WILLIAM K. ANDERSON, a citizen of the United States, residing at Colorado Springs, in the county of El Paso and State of Colorado, have invented 5 certain new and useful Improvements in Rail-Joints, of which the following is a specification, reference being had to the accompanying drawings.

10 My invention relates to rail joints and particularly to that character of rail joint wherein a member is provided which engages the base of two abutting rails and holds said rails in alinement.

15 The primary object of my invention is the provision of a very simple joint of this character which may be cheaply made and which will be particularly effective in holding the rails in alinement and which will also act to 20 support the rails at the joint and prevent one of the rails from being deflected downward relative to the other rail.

A further object of the invention is to 25 provide a joint of this character which may be readily attached to or detached from the rails and still another object is to provide a joint of this character which, while holding the rails in vertical alinement with each other, will permit the rails to move bodily 30 to accommodate expansion and contraction of the rails.

Still another object is to provide a joint of such a simple character and so easily applied that it may be used for mine railroads.

35 My invention is illustrated in the accompanying drawings wherein—

Figure 1 is a side elevation of a rail and rail chair constructed in accordance with my invention, the chair being partly in section, and the splice bar being broken away; 40 Fig. 2 is a transverse section of the joint. Fig. 3 is a section on the line 3—3 of Fig. 1.

45 Referring to these drawings, 2 designates abutting rails of the usual character and each formed with a base flange 3, a web 4, and a head 5. Each of these rails is made with a plurality of perforations 6 passing through the webs of the rails.

Disposed beneath the abutting ends of the 50 rails and extending longitudinally therealong is a joint chair designated 7. This chair is provided with the rail seat 8 and the upwardly and inwardly extending rail engaging flanges 9 and 10. The flange 10 55 extends upward higher than the other flange and is formed with the upwardly and in-

wardly inclined face 11. This chair is also provided with the transversely extending passages 12, there being preferably four passages altogether, two passages beneath 60 each rail. These passages are relatively wide as shown in Fig. 1 and the passages are so disposed that the bases of the rails intersect them. Adapted to be disposed within these passages are the wedges 13. 65 These wedges are preferably flat upon the bottom, slightly inclined upon the top, and the upper face of the wedge is preferably formed with upwardly extending ribs 14. The end of each wedge is preferably formed 70 with a head 15. The wedges it will be seen are narrower than the width of the openings 12 so that the wedges may have lateral movement relative to the openings. When these wedges are driven into place the 75 toothed or ribbed upper faces of the wedges will bite against the under face of the base of the rail and the wedges will be thus locked to the rail and as a consequence will move with the rail as it expands or contracts, this movement being permitted by 80 the wedges being smaller than the openings 12 as previously stated.

In order to lock the rails within the chair from longitudinal movement relative to each other I provide a splice bar 16. This splice bar is formed to fit between the web 4 of the rail and the adjacent inclined face 11 of the flange 10 and to fit against the base of the rail and beneath the head thereof. Each 90 splice bar is provided with a plurality of inwardly extending pins 17 which are designed to fit within the openings 6 formed in the web of the rail.

With the parts as above described it is 95 obvious that two abutting rails will be locked securely to each other and to the chair which supports the abutting ends of the rails. In placing the parts in position the chair is first disposed upon one of the rails and shifted to a position inward of the end of the rail. The other rail is then abutted against the first named rail and the splice bar is put in place whereupon the chair is shifted along the rail until it engages firmly with the splice bar, forcing it firmly against the web of the rail. After this the wedges 13 are driven home, locking all the parts together. In order to hold the wedges from accidental detachment I may 100 provide the locking member 18 which is formed of a strip of metal disposed along 105 the rail seat 8. The member 18 is disposed 110

the under face of each wedge, this strip being bent up at one end as at 19 against the head of the wedge and its other end being bent downward as at 20 against the side of the chair. It will, of course, be plain that this locking strip 18 will hold the wedges securely in place against accidental detachment.

It is to be particularly noted, as shown in Fig. 3, that the space between the rail seat 8 and the under face of the flange 9 is less than the space between the seat 8 and the under face of the flange 10. This difference is of considerable importance in the practical use of my construction. Before the wedge members 13 are inserted, the space between the upwardly inclined face 11 of flange 10 and the face of the web 4 will be greater than the thickness of the splice bar, thus permitting the splice bar and rail to be readily inserted in place. Now when the wedges 13 are driven into place they will force the chair down relative to the rail and the inclined face 11 will force the rail and splice bar laterally. The base of the rail will be forced against the chair at 8, and as the space between the flange 10 and the seat is deeper than between the flange 9 and the seat the adjacent edge of the rail base 3 will spring upward, thus binding the rail and chair tightly together for holding the rails in alignment.

While my device is adapted for use on railway tracks and in like situations, it is also particularly adapted to be used on mine tracks. In this case ordinary track spikes may be used for the wedges.

Having described my invention what I claim is:

- 40 1. In a rail joint, abutting rails having transverse perforations in their webs, a chair supporting the rails at the joint and having upwardly extending flanges, a rail engaging member disposed between one of said flanges and the web of the rails, and transversely extending locking members extending through passages formed in the chair beneath the base of the rail, said locking members having engagement with the base of the rail.
- 45 2. In a rail joint, abutting rails, a rail chair disposed beneath the joint between said rails and having upwardly extending flanges, a splice bar disposed between one of said flanges and the web of the rail and having interlocking engagement with the web of the rail, and wedges extending transversely through the chair and beneath the base of the rail, each wedge having longitudinally extending teeth upon its upper surface adapted to bite into the rail.
- 50 3. In a rail joint, abutting rails, each formed at one end with transversely extending perforations, a rail chair extending beneath said rails at their joint and having upwardly and inwardly extending angular flanges adapted to embrace the base of the rail, a splice bar disposed between one of said flanges and the web of the rail and having inwardly extending pins adapted to be disposed in the perforations in the rail web, the chair being formed with transversely extending passages intersecting the upper face of the chair, and wedges driven through said passages and engaging the under face of the rail base, said wedges having a width less than the length of said passages whereby the wedges may be shifted upon the expansion or contraction of the rails.
- 55 4. In a rail joint, a chair having oppositely disposed overhanging flanges adapted to engage the base of a rail, a wedging member disposed between one of the overhanging flanges and the web of the rail and resting upon the base flange thereof, and means for forcing a rail supported in the chair upward against the flanges to simultaneously raise said wedging member to thereby wedge the rail laterally within the chair and lock it in engagement therewith.
- 60 5. In a rail joint the combination with abutting rails having perforations in their webs, of a chair adapted to support said rails at the joint thereof and formed with upwardly and inwardly extending flanges adapted to embrace the base of the rails, one of said flanges being formed with an upwardly and inwardly inclined face, a splice bar having a downwardly and outwardly inclined outer face adapted to be disposed between said flange and the web of the rail and having studs projecting into the perforations in the rail web, the chair being formed with transversely extending passages intersecting the upper face of the chair, and wedges driven into said passages and engaging the base of the rail, said wedges having longitudinally extending teeth upon their upper faces, the width of the wedges being less than the width of the passages.
- 65 6. In a rail joint, abutting rails, a chair supporting the rails at the joint and having inwardly turned base engaging flanges, said chair being formed with a plurality of transversely extending passages intersecting the upper face of the chair, wedges driven into said passages and engaging the base of a rail, and means for holding the wedges in place comprising a metallic strip disposed in each passage beneath the corresponding wedge, one end of the strip being turned down to engage the chair, and the other end of the strip being bent to engage the head of the wedge.
- 70 7. In a rail joint the combination with a rail, of a chair adapted to support the rail and having an upwardly and inwardly extending flange, the inner face of said flange being downwardly and outwardly inclined, a rail engaging member disposed between

110

130

lar flanges adapted to embrace the base of the rail, a splice bar disposed between one of said flanges and the web of the rail and having inwardly extending pins adapted to be disposed in the perforations in the rail web, the chair being formed with transversely extending passages intersecting the upper face of the chair, and wedges driven through said passages and engaging the under face of the rail base, said wedges having a width less than the length of said passages whereby the wedges may be shifted upon the expansion or contraction of the rails.

4. In a rail joint, a chair having oppositely disposed overhanging flanges adapted to engage the base of a rail, a wedging member disposed between one of the overhanging flanges and the web of the rail and resting upon the base flange thereof, and means for forcing a rail supported in the chair upward against the flanges to simultaneously raise said wedging member to thereby wedge the rail laterally within the chair and lock it in engagement therewith.

5. In a rail joint the combination with abutting rails having perforations in their webs, of a chair adapted to support said rails at the joint thereof and formed with upwardly and inwardly extending flanges adapted to embrace the base of the rails, one of said flanges being formed with an upwardly and inwardly inclined face, a splice bar having a downwardly and outwardly inclined outer face adapted to be disposed between said flange and the web of the rail and having studs projecting into the perforations in the rail web, the chair being formed with transversely extending passages intersecting the upper face of the chair, and wedges driven into said passages and engaging the base of the rail, said wedges having longitudinally extending teeth upon their upper faces, the width of the wedges being less than the width of the passages.

6. In a rail joint, abutting rails, a chair supporting the rails at the joint and having inwardly turned base engaging flanges, said chair being formed with a plurality of transversely extending passages intersecting the upper face of the chair, wedges driven into said passages and engaging the base of a rail, and means for holding the wedges in place comprising a metallic strip disposed in each passage beneath the corresponding wedge, one end of the strip being turned down to engage the chair, and the other end of the strip being bent to engage the head of the wedge.

7. In a rail joint the combination with a rail, of a chair adapted to support the rail and having an upwardly and inwardly extending flange, the inner face of said flange being downwardly and outwardly inclined, a rail engaging member disposed between

the rail and the inner face of the flange and having an upwardly and inwardly inclined face, and means engaging the rail and chair and urging the rail upward to thereby carry 5 the rail engaging member into wedging engagement with the adjacent flange.

8. In a rail joint, a rail chair, said chair having a rail seat and upwardly and inwardly extending flanges spaced from the 10 seat, the chair being formed with transverse passages extending below and intersecting the seat, rail engaging members disposed in said passages and adapted to urge the rail upward in a space against the flanges, a 15 splice bar adapted to be disposed between one of said flanges and the rail, the adja-

cent face of the splice bar and said flange being upwardly and inwardly extended, the space between said seat and the adjacent face of the splice bar engaging flange being 20 greater than the space between said seat and the adjacent face of the opposite flange whereby to cause a tipping of the rail upon the insertion of said rail engaging members and the locking of the splice bar and 25 rail to the chair.

In testimony whereof I hereunto affix my signature in the presence of two witnesses.
